UNITED STATES PATENT OFFICE.

DANIEL McFARLAN MOORE, OF EAST ORANGE, NEW JERSEY, ASSIGNOR TO GENERAL ELECTRIC COMPANY, A CORPORATION OF NEW YORK.

VAPOR ELECTRIC DEVICE.

1,255,549.

Specification of Letters Patent.

Patented Feb. 5, 1918.

Application filed June 16, 1915. Serial No. 34,524.

To all whom it may concern:

Be it known that I, DANIEL McFARLAN MOORE, a citizen of the United States, residing at East Orange, county of Essex, State of New Jersey, have invented certain new and useful Improvements in Vapor Electric Devices, of which the following is a specification.

My present invention relates to devices of the class in which an electrical discharge is caused to pass between electrodes in a vessel containing a rarefied gas or vapor and more particularly to devices of this character in which the electrical discharge is of such a nature that the gas or vapor is rendered luminous and hence the device may be used as a source of artificial light.

An object of my invention is to produce a gaseous conduction device in which the gas pressure is maintained substantially constant by means of an arrangement which automatically produces more gas in the device as fast as the gas present therein is used up by the passage of the discharge. A further object of my invention is to produce a device of this nature which is adapted for operation on constant potential alternating current circuits or on constant current circuits, either alternating or direct.

In carrying my invention into effect I provide, within the tube or other receptacle which serves as a container for the rarefied gas or vapor, a quantity of a substance which when heated will evolve the desired gas. I also provide a means for heating this material which is dependent upon the gaseous conduction current flowing through the tube. In the preferred form of my invention this heating means comprises a coil of wire embedded in the gas evolving material and connected in a shunt circuit to the main circuit which includes the electrodes of the tube. Current for the main and shunt circuits is supplied by a constant current source. When the gas pressure in the tube falls below the desired amount the current between the electrodes will decrease and consequently the shunt current will increase. As a result the gas evolving material will become more highly heated and will give off more gas, restoring the pressure in the tube to the desired value.

My invention, with further objects and advantages, will best be understood by reference to the following description taken in

connection with the accompanying drawing in which Figure 1 is an elevation of a complete lamp constructed in accordance with my invention; Fig. 2 is a bottom view of the lamp shown in Fig. 1; Fig. 3 is a diagrammatic representation of the electrical connections of the lamp, Fig. 4 is a fragmentary view illustrating a modified form of electrode, and Fig. 5 is a cross sectional view taken along the line 5—5 of Fig. 1.

As indicated in the drawings my lamp comprises a sealed tube 1 having at each end thereof similar electrodes. While I have indicated the tube in the present case as being straight it will be apparent that it may be given any form desired to vary the amount of light radiating surface and the light distribution. This tube may be mounted in a metal casing open at the bottom and preferably provided with a reflector on its under side. Since the light giving portion of the tube consists only of that portion between the electrodes the portion of the tube containing the electrodes may be entirely inclosed by the casing if desired. The casing 3 may conveniently be attached to the casing 4, which protects the transformer 5 (indicated by dotted lines) by a plug and socket connection 6 which serves also to electrically connect the transformer and the tube. It will of course, be apparent that the casing here shown can be utilized for other tubular lamps than the one illustrated and described herein.

The tube 1 also contains between the electrodes 2 and the sealed ends a quantity of material which gives off gas when heated. This material is preferably inclosed in a capsule 7 provided with one or more openings to allow the gas evolved to pass into the tube 1. A heating coil 8 within the capsule is embedded in the gas evolving material. While this is the preferred location for the gas evolving material it may equally well be placed in a side tube connected to the main tube 1. In any case it should be so located that it will not be affected by the heat of the discharge between the electrodes. The heating coil should preferably be composed of some high resistance, high melting point non-oxidizing alloy. As indicated in Fig. 3 the heating coils at the ends of the tube are connected in series with each other and with regulating resistances 9 across the secondary 10 of the transformer 11.

5 in a circuit which is in shunt to the circuit which includes the electrodes 2, 2, and the intervening gas column. This transformer is preferably designed so as to have large 10 leakage between the primary and secondary in order to give a substantially constant secondary current. If desired the regulating resistance may be dispensed with by providing extra taps on the secondary of the transformer so that the full secondary voltage 15 will not be applied to the heating circuit. Such an arrangement will not affect the method of operation of the device. While I have described my device in connection with its operation on constant potential circuits 20 it will be apparent that it is equally well adapted for operation on constant current series circuits. Although I have shown a single lamp connected to the secondary of the transformer a plurality of lamps may be connected in parallel with the secondary of the transformer if desired. Also by placing a ballast device, such for example as an inductance, in series therewith either a 25 single lamp or a plurality of lamps in parallel may be operated from the secondary of a transformer giving substantially constant potential.

In the form of my invention illustrated in 30 Fig. 4 I place a filamentary portion 11 of the electrode in series with the heating coil 8 in order to heat it to incandescence. This portion of the electrode will then serve as cathode for the discharge while the remaining portion which is heated only by the discharge will be cooler at all times and will serve as anode. This portion 11 of the electrode will preferably be composed of tungsten or other refractory metal. It will of 35 course be apparent that the filamentary portion 11 may also be connected in series with the other portion of the electrode so that it will be heated by the discharge current. The electrodes 2 may be composed of aluminum, 40 tungsten, molybdenum, or other metals, the choice of the metal to be used depending to some extent upon the gas which is to be employed in the tube. The gas evolving material to be used will of course depend upon 45 the gas desired. If carbon dioxid is to be employed the heating coils 8 may be embedded in any carbonate which gives off carbon dioxid when heated. Calcium carbonate (CaCO_3) is especially suitable for 50 this purpose. A lamp in which pure carbon dioxid is employed is especially valuable for color matching equipments inasmuch as it gives a light which is nearer to daylight than that from any other known artificial 55 source. If nitrogen is to be used the gas evolving substance may consist of a nitride which gives off nitrogen when heated. If neon or other inert gas is to be used the substance employed may be charcoal, platinum 60 sponge or other material which will absorb 65

gas when cold and give it off again when heated.

The life of a lamp of this type will of course depend upon the amount of gas evolving material which is placed in the 70 tube in such a way that it will be heated by the coils 8 as well as upon the particular material and gas used. I have found, however, that such a lamp may be given a reasonably long life without making the 75 space occupied by the gas evolving material relatively large in comparison with the light emitting part of the tube.

While I have described my invention with particular reference to one specific form of 80 lighting device, it will be apparent that it is equally applicable to any form of electrical discharge device in which a discharge takes place between electrodes in a rarefied 85 gas or vapor and in which to keep the discharge constant it is necessary to maintain the gas or vapor at a substantially uniform density.

What I claim as new and desire to secure by Letters Patent of the United States is:— 90

1. The combination in a gas electric lamp of a tubular receptacle containing a rarefied gas, electrodes within said receptacle, a source of constant current connected to said electrodes and adapted to produce a luminous discharge through the rarefield gas, material within said receptacle which evolves 95 gas when heated, a permanently closed heating coil embedded in said gas evolving material, and a closed circuit in shunt to said electrodes which includes said heating coil, the resistance of said circuit being so adjusted that the current flowing therein will vary in such a way as to keep the density of the gas in said receptacle substantially constant. 100

2. The combination in a gaseous conduction device of a receptacle containing a column of rarefied gas, electrodes within said receptacle, means for causing a discharge current to pass through said gas column between said electrodes, material within said receptacle which evolves gas when heated, a heating coil embedded in said gas evolving material and means for causing a current to flow through said heating coil which varies in such a way as to keep the density of the gas in said receptacle substantially constant. 110

3. The combination in a gaseous conduction device of a receptacle containing a rarefied gas, electrodes within said receptacle, a source of constant current connected to said electrodes to produce an electrical discharge through the rarefied gas, a second receptacle in communication with the first receptacle and containing a material which evolves gas when heated, and a heating circuit in shunt to the circuit between said electrodes for heating the gas evolving material to 115 120 125 130

such a degree as to maintain the density of the gas substantially constant.

4. The combination in a gaseous conduction device of a receptacle containing a rarefied gas, electrodes within said receptacle, a source of constant current connected to said electrodes to produce an electrical discharge through the rarefied gas, a second receptacle in communication with said first receptacle but removed from the path of the electrical discharge and containing a material which evolves gas when heated, and a permanently closed heating circuit in shunt to the circuit between said electrodes for heating the gas evolving material to such a degree as to maintain the density of the gas substantially constant.

5. The combination in a gaseous conduction device of a receptacle containing a rarefied gas, electrodes within said receptacle, a source of constant current connected to said electrodes to produce an electrical discharge through the rarefied gas, a second receptacle in communication with the first receptacle but removed from the path of the electrical discharge and containing a material which evolves gas when heated, and a heating coil embedded in said gas evolving material and connected in shunt to the circuit between said electrodes.

6. The combination in a gas electric lamp of a tubular receptacle containing a rarefied gas, electrodes near the ends of said receptacle, a source of constant current connected to said electrodes to produce a luminous discharge through the rarefied gas, a second receptacle with said first receptacle, between one of the electrodes and the corresponding end of the receptacle, containing a material which decomposes when heated and evolves gas and a heating coil embedded in said gas evolving material and connected in shunt to the circuit between the electrodes.

7. The combination in a gaseous conduction device of a receptacle containing a rarefied gas, electrodes within said receptacle

having filamentary portions, a source of constant current connected to said electrodes to produce an electrical discharge through the rarefied gas, material within said receptacle which evolves gas when heated, a heating coil embedded in said gas evolving material and a heating circuit in shunt to the circuit between said electrodes for heating the gas evolving material and the filamentary portions of the electrodes.

8. A vacuum tube having therein gas evolving material and a heating element embedded in said gas evolving material, said heating element being connected in a permanently closed circuit in shunt to said tube.

9. A vacuum tube having internal electrodes, a capsule therein containing gas evolving material and a heating element embedded in said gas evolving material, said heating element being connected in a permanently closed circuit in shunt to said tube.

10. A vacuum tube having internal electrodes, a receptacle containing gas evolving material in communication with the interior of said vacuum tube and a heating element embedded in said gas evolving material, said heating element being connected in a permanently closed circuit in shunt to said tube.

11. A vacuum tube having internal electrodes and containing a gas which is rendered luminous by an electrical discharge between said electrodes, a receptacle in communication with the interior of said vacuum tube and containing a material which, when heated, evolves a gas suitable for replenishing the gas in the tube and a heating element embedded in said gas evolving material, and connected in a closed shunt circuit to said electrodes.

In witness whereof, I have hereunto set my hand this 14th day of June, 1915.

DANIEL McFARLAN MOORE.
